Primary Examiner — Mark Goodwin

(57) **CLAIM**

The ornamental design for the door frame universal bracket, as shown and described.

DESCRIPTION

FIG. 1. Is a top perspective view of a door frame universal bracket showing my new design;

FIG. 2. Is a top view thereof;

FIG. 3. Is a backside view thereof;

FIG. 4. Is a front view thereof;

FIG. 5. Is a front side view from the left thereof;

FIG. 6. Is a front side view from the right thereof; and,

FIG. 7 is a reduced perspective view thereof shown in use condition.

The broken line showing in FIG. 7 of an extra door frame universal bracket and a door frame is included for the purpose of illustrating environmental structure only and forms no part of the claimed design.
